UNITED STATES PATENT OFFICE

165,580

FOUNDATION VENTILATOR GRILLE

Lewis W. Hamlin, Little Rock, Ark.

Continuation of abandoned design application
Serial No. 15,744, July 2, 1951. This application
November 2, 1951, Serial No. 17,247

Term of patent 14 years

(Cl. D62—4)

To all whom it may concern:

Be it known that I, Lewis W. Hamlin, a citizen of the United States, residing at Little Rock, Arkansas, have invented a new, original, and ornamental Design for a Foundation Ventilator Grille, of which the following is a specification, reference being had to the accompanying drawing, forming part thereof. This is a continuation of my application Serial No. D. 15,744, filed July 2, 1951, now abandoned.

Figure 1 is a front elevational view of a foundation ventilator grille showing my new design;

Figure 2 is a rear elevational view of the grille;

Figure 3 is a top plan view of the grille; and

Figure 4 is a side elevational view of the grille.
I claim:
The ornamental design for a foundation ventilator grille, as shown.

LEWIS W. HAMLIN.
